UNITED STATES PATENT OFFICE.

CHARLES W. POTTER, OF WALTHAM, MASSACHUSETTS, ASSIGNOR TO THE POTTER PRESS, OF BOSTON, MASSACHUSETTS, A CORPORATION OF MASSACHUSETTS.

SALES-BOOK.

1,164,748.

Specification of Letters Patent. Patented Dec. 21, 1915.

Application filed February 7, 1914. Serial No. 817,140.

To all whom it may concern:

Be it known that I, CHARLES W. POTTER, a citizen of the United States, residing at Waltham, in the county of Middlesex and 5 State of Massachusetts, have invented certain new and useful Improvements in Sales-Books; and I do hereby declare the following to be a full, clear, and exact description of the invention, such as will enable others 10 skilled in the art to which it appertains to make and use the same.

The present invention relates to sales books, and more particularly to a sales book having an improved device for securing the 15 sales pad in the sales pad cover.

The object of the invention is to cheapen the cost of sales books.

To this end the invention consists in the sales book having an improved and cheaply 20 manufactured device for securing the sales pad in the said cover, hereinafter described and particularly pointed out in the claims.

In the drawings illustrating the preferred embodiment of the invention, Figure 1 is a 25 perspective view showing the way in which the sales pad is inserted in the sales pad cover and Fig. 2 is a fragmentary side elevation of the sales book with the sales pad in place.

The illustrated sales book consists of a 30 sales pad 1 and a sales pad cover 2. The sales pad comprises a number of paper leaves 5 and a tag board back 6. The leaves 5 and tag board back 6 are bound or stapled together at their top margins by the usual 35 wire stitches 7. The leaves 5 are torn out as used. This form of pad is the usual sales pad employed by tradesmen. The sales pad cover 2 has top and bottom covers 10 and 11, 40 hinged together by a flexible back 12. For the purpose of securing the sales pad in the sales pad cover, two separate sheet metal clips 15 are fastened at the opposite edges of the bottom cover 10 by means of rivets 16. 45 Each sheet metal clip consists of a base plate 17 which lies flat against, and is secured to, the bottom cover, or sales pad support, 10, a pad-engaging tongue 18 (overlying the support) which extends inwardly from the edge 50 of the clip base and an upstanding lip 19.

When the sales pad is inserted in the sales pad cover, the tag board back 6 is inserted beneath the tongues 18 and the sales pad is drawn in, as shown in Fig. 1, until the 55 tongues which extend between the back 6

and the leaves 5, are brought into engagement with the inside of the stitches 7. In this position, the top or bound edge of the sales pad which is adjacent to the stitches 7 fits inside the lips 19 as shown in Fig. 2. 60 The tongues 18 by their engagement with the stitches 7, and the lips 19 by their engagement with the top edge of the sales pad, prevent the sales pad from moving longitudinally, and the tongues 18 engage and 65 hold the edges of the tag board back 6 and prevent the sales pad from moving laterally in the sales pad cover. The sales pad is thus securely held in place. When the leaves are all torn off of the sales pad, the 70 tag board back is easily removed from the cover. In case it is desired to remove the sales pad before it is used up, the edge of the pad adjacent the lips 19 may be lifted by catching it with the finger or thumb at 75 the middle of the edge between the two lips 19 and the sales pad drawn out over the tops of the lips 19. The clips 15 are stamped out of sheet metal and are very cheap to manufacture. Moreover, the same clips may 80 be used on widely varying sizes and shapes of covers, all of which conduces materially to cheapen the cost of manufacturing the sales books.

The present invention is not limited to the 85 illustrated embodiment as it may be embodied in other constructions within the scope of the following claims:

1. A sales book having, in combination, a sales pad comprising a number of leaves, a 90 board back and stitches passed through the leaves and back near one edge of the pad, and a sales pad cover having fixed inwardly extended tongues for engaging the pad between the leaves and the back adjacent to 95 the stitches, and an upstanding lip engaging the adjacent edge of the pad, substantially as described.

2. A sales book having, in combination, a 100 sales pad comprising a number of leaves, a board back and stitches passed through the leaves and back near one edge of the pad, and a sales pad cover having two sheet metal clips rigidly secured to the inside of the 105 cover at its opposite edges, each clip having a flat base secured to the cover, an inwardly extended tongue engaging the pad between the leaves and the back adjacent to the stitches and an upstanding lip at the edge of the base for engaging the edge of the pad 110.

adjacent to the stitches, substantially as described.

3. As an article of manufacture a clip for use in making pad holders consisting of a flat base having an upstanding lip adapted to engage the bound edge of a pad and a tongue secured to the base at an edge thereof and extended from the said edge inward from the edge and close to the base so as to hold a portion of the pad between the tongue and the base, the tongue and lip coöperating to hold the pad in place, substantially as described.

4. A sales pad holder having, in combination, a support for a pad and a pair of separate clips secured to the support having upstanding lips arranged in line with each other to engage a bound edge of a pad, and tongues overlying the support adapted to engage a portion of the pad, substantially as described.

5. A sales pad holder having, in combination, a support for a pad, and a pair of separate clips secured to the support having fixed pad-engaging tongues overlying the support and arranged parallel and close to the support, to engage the pad close to a bound edge thereof, substantially as described.

6. A sales pad holder having, in combination, a support for a pad and a pair of separate clips secured to the support having fixed pad-engaging tongues and upstanding lips, the pad-engaging tongues overlying the support and arranged parallel and close to the support and the upstanding lips arranged parallel to the pad-engaging tongues.

CHARLES W. POTTER.
